UNITED STATES PATENT OFFICE.

G MURL GORDEN, OF PORTLAND, OREGON.

CASH-REGISTER SYSTEM.

1,420,311.

Specification of Letters Patent. Patented June 20, 1922.

Application filed June 15, 1920. Serial No. 389,146.

To all whom it may concern:

Be it known that I, G MURL GORDEN, a citizen of the United States, residing at Portland, in the county of Multnomah and 5 State of Oregon, have invented certain new and useful Improvements in a Cash-Register System, of which the following is a specification.

This invention has for its object the provision of means for automatically effecting 10 the substantially simultaneous actuation of two or more cash registers and similar machines, whereby the manually effected operations of one register are promptly and 15 accurately transmitted to and duplicated in a remote register to afford the attendant of the latter reliable indication of the frequency and amount of sales represented by the operations of the first mentioned register.

With this and other objects in view, the invention consists in certain novel features of construction as hereinafter shown and described and then specifically pointed out 25 in the claims, and in the drawings illustrative of the preferred embodiment of the invention.

Figure 1 represents a perspective view illustrating fragments of two cash registers 30 and illustrating the invention as applied thereto, and.

Figures 2 and 3 represent fragmental side elevations of the registers illustrating the invention.

Referring to the drawing in detail, wherein similar reference numerals designate corresponding parts throughout the several views, the numerals 5 indicate portions of the key levers which in the conventional types of registers are arranged in 35 banks or rows.

The numerals 6 indicate the corresponding levers of another or secondary register which is remotely located relative to the 45 levers 5 of the first named register and are automatically actuated thereby.

A contact 7 is arranged below and in the path of each of the key levers 5 and consists of a casing 8 receiving an expansible 50 coil spring 9 confined between the bottom of the casing and a vertically movable button 10 which is adapted to be engaged and depressed by the key levers 5. Each contact 7 is rigidly secured to a suitable support 11 55 by a bolt 12 which latter constitutes a binding post for one terminal of a wire forming

part of an electrical circuit to be herein-after more fully described.

An axially elongated ratchet wheel 13 is rotatably supported beneath the row of key 60 levers 6 of the secondary cash register and the teeth thereof are arranged to engage pawls 14 pivotally secured at 15 to the levers 6. The pawls are normally maintained in retracted or inoperative position by contractile springs 16.

A series of electromagnets 17 corresponding in number to the number of key levers 6 is arranged in front of each bank or row and has associated therewith an armature 70 18 carried by a pivoted arm 19 suitably supported at 20 for swinging movement in the direction of the axis of the magnets. The upper terminals of the pivoted arms are connected by links 21 with the pawls 14 and the 75 arrangement of the electromagnets 17 is such that when energized, they effect forward movement of the armatures 18 by magnetic attraction and shift the arms 19 so as to move the pawls 14 into operative relation to the teeth of the ratchet wheel 13.

During the period of operation of the cash registers, the ratchet wheel 13 is constantly rotated at a required speed for such purpose by a motor 22 having connection with 85 the wheel through a belt or other power transmitting device 23 so that as one or more of the pawls 14 of the key levers 6 are moved into operative relation with the ratchet wheel 13 the same exerts a downward pull upon 90 the pawl or pawls engaged thereby and effects an automatic depression of the key lever for the consequent actuation of the registering mechanism of the cash register.

It is to be here noted that, in addition to 95 the speed of the ratchet being sufficient to effect proper engagement of the pawls 14 therewith, regardless of the time period of the depression of the cash register levers 5 for the closing of the circuits through the 100 magnets 17, the contacts 7 are spring sustained to give a retarded downward movement to the levers 5, and, upon the release of the latter by an operator, remain in contact therewith during the major upward movement of the same to final circuit breaking position, which time period of operation of the magnet 17 is entirely satisfactory to assure of the pawls 14 being actuated into the path of the ratchet wheel 13.

A deflecting finger 24 is arranged beneath each pawl 14 and is so disposed as to

retract the pawl from the teeth of the ratchet wheel 13 as the key lever 6 approaches the limit of its downward movement.

One pole of a battery 25 or other source 5 of electro-motive force is connected by conductors 26 with one terminal of the electro-magnet coil 17 whereas the opposite pole of the battery is connected by a conductor 27 with each of the key levers 5 of the main or 10 primary cash register. The opposite terminals of the coils of the magnets 17 are connected by conductors 28 with the binding post 12 and, as will be understood, the key levers 5 are constructed of metal or such conducting material. 15

Each contact 7 is separately connected with its respective electromagnet 17 by an individual conductor 28 whereby the manual actuation of any one of the key levers 5 in 20 the primary cash register produces automatic energization of the electromagnet 17 controlling the operation of the corresponding key lever 6 in the secondary cash register.

The invention is especially designed for 25 utilization in mercantile establishments wherein it is desirable to reproduce in the office of the establishment the successive operations of the cash registers located in various departments. Furthermore, by this arrangement of cash registers the person in 30 charge of the distribution of sales people may readily determine the condition of business in each department and thereby main-

tain a suitable force to carry on the business, according to the volume of the latter.

What I claim is:

1. In combination, primary and secondary registering machines each including key levers, pawls connected to the levers of the secondary registering machine, rotating 40 means engageable with the pawls for effecting automatic actuation of the key levers of the secondary registering machine, electro-magnetic means for moving the pawls into operative relation with the last mentioned 45 means, and means actuated by the key levers of the primary registering machine for controlling the magnetic means.

2. In combination, primary and secondary registering machines each including a plurality of key levers, pivoted pawls carried by the key levers of the secondary machine, rotating means engageable with said pawls for effecting an automatic operation of the key levers of the secondary registering machine, means constantly actuating said rotating means, electromagnetic means for moving the pawls into operative relation with the first mentioned means, a normally open electrical circuit for each of the magnetic means, and means controlled by the key levers of the primary registering machine for controlling said circuit. 55

In testimony whereof, I affix my signature hereto.

G MURL GORDEN.
